UNITED STATES PATENT OFFICE.

JOHN O. HUNT, OF BROOKLYN, NEW YORK, ASSIGNOR TO INDEPENDENT PAPER MILLS,
INC., OF BROOKLYN, NEW YORK.

BANDING MACHINE.

Application filed April 20, 1926. Serial No. 103,193.

This invention relates to banding mechanisms and particularly to machines for applying a tape-like strip of paper, as a band, about packages of like size.

5 In the commercial manufacture of high grade paper napkins or serviettes a bibulous paper is received in the form of a large roll from the mill, slit into sheets of desired width, folded and cut transversely into 10 squares of suitable size and thereafter folded, doubled and redoubled into smaller squares, familiar to all and sold in this condition to restaurants and supply houses in packages containing a definite number.

15 The purpose of the present invention is to provide an efficient mechanism to receive the loosely folded napkins in bunches of a predetermined number, pass a narrow strip 20 of paper around the napkins, sever the strip from the roll on which it is wound, apply an adhesive to one of the engaging ends of the strip, press the ends together to cause cohesion and deliver the packages thus 25 formed outwardly from the machine in condition to be boxed for shipment.

It is an object to perform these several functions consecutively, without waste of band material, to apply the adhesive without making contact with the napkins, which 30 should pass through the machine without human touch or becoming soiled, and which are thus bound at a high rate of speed.

Such results are fully attained by the mechanism hereinafter described and illustrated in the associated drawings, forming an essential part of this disclosure, and in which:—

Fig. 1 is a side elevational view of an embodiment of the invention, the packing 40 plunger being in a raised rearward position.

Fig. 2 is a similar view of the same but showing the plunger in its lowermost position and the beam head extending thereover.

Fig. 3 is a front elevational view of the 45 packaging mechanism resting on the parts illustrated in Fig. 1 and showing the napkin gathering, adjusting and compressing means in receptive position.

Fig. 4 is another like view of the same 50 showing the parts as engaged with the napkins as illustrated in Fig. 2.

Fig. 5 is a perspective view of the stacked napkins partially wrapped in a binder.

Fig. 6 is an enlarged detail view in side 55 elevation of the beam head.

Fig. 7 is a top plan view of the beam showing its swinging supports, rack actuated parts, and geared adhesive applying device carried thereon.

Fig. 8 is a side elevational view of the 60 same, showing the racks and elements operated thereby, certain parts being omitted to avoid confusion.

Fig. 9 is an enlarged partial sectional, 65 partial side elevational view of the rack actuated tape cutter and adhesive applicator, the section being taken substantially on line 9—9 of Fig. 12.

Fig. 10 is a transverse sectional view 70 taken on line 10—10 of Fig. 8, showing the paper tape roll support as carried by the beam, and pinion engaged with the beam rack.

Fig. 11 is a similar sectional view taken 75 on line 11—11 of Fig. 8, through the adhesive supply tank and dispensing roll therein.

Fig. 12 is a like sectional view taken on line 12—12 of Fig. 8, through the rack 80 driven adhesive applicator and cutter blade carrying wheel.

The mechanism for packaging the napkins is to be understood as adjunctive to other devices for cutting, folding, counting and bunching them in prior operations and 85 consists of an upright frame, generally designated by the numeral 20, having a plain upper wall 21 and a flat surfaced wide column 22 at the front end.

At the top of the column 22 is a block 23, 90 in which is mounted a pair of spaced transverse spindles 24 and 25 carrying counting and bunching mechanism for the napkins, not constituting part of this invention.

Extending through the wall 21 are a pair 95 of shafts 26 and 27 spaced in parallel and rotated in unison at the same speed in opposite directions; adjustably mounted on the shaft 26 is a crank 28 having a reduced stem 30 and on the shaft 27 is fixed a disc 29 100 carrying a crank pin 31, the stem and pin being in direct angular opposition with reference to the axes of the shaft.

Mounted to rotate on the stem 30 is a flat rectangular plate 32 to which is bolted the 105 reduced end of a block 33 having a flange 34 at its outer end, and adjacent thereto is another block 35 having flanges at both ends.

The block 33 is slidably mounted in a slot 110 36 formed lengthwise in a plate bar 37 hav-

ing on its upper outer side a reenforcing rail 38.

Slidably seated on the upper flanged edges of the block 35 is an I shaped rail 39, having attached on its outer surface a rack 40 with teeth on both its upper and lower surface, and beyond the rack is a second plate bar 41 adjacent to which is another rack 42, attached to the block 35 and having upwardly disposed teeth.

Journalled on a stud bolt 43, carried by the plate bar 41, is a spur pinion 44, its teeth engaging both racks 40 and 42, between which it operates, the plate bars being slidably connected at intervals by clips 45 and 46.

Bolted to the plate bars 37 and 41 are a pair of raised supports 50, offset inwardly above the upper edges of the plates and having open central vertical slots 51 to receive the ends of a shaft 52 on which a roll of narrow tapelike paper banding 53 is carried.

At a point further to the front on the beam, constituted by the bars 37, 41 and rail 39, the crank stem 31 passes through an opening therein, in the plane of the slot 36 and is secured by a nut at its outer end.

It will now be apparent that the beam, as an entity, is given a gyratory movement around the axes of the shafts 26 and 27 and is retained throughout in a level horizontal position; motion is transmitted by the crank pin 31, the crank stem 30 acting as a suspending means, due to its connection within the slot.

The front portion of the beam is increased in thickness at its bottom and fixed on the crank stem 31, between the beam sides, are a pair of cams 54 having a single throw, 40 these cams engaging lugs 55 formed on levers 56 curved to clear the cams and pivoted at 57 to the beam at opposite sides; the radial arms 58 of these levers terminate in downturned extensions 59 near the end of 45 the beam, the function of which will later appear, the levers being drawn upwardly to cause engagement with the cams by tension springs 60.

Rearward of the pivots 57 a pair of plate brackets 61 are secured on the beam sides, the raised rear portions being slotted to receive a spindle 62 on which is fixed a disc roll 63, having a portion of its knurled periphery entering an open tray-like container 64, provided with an adjustable wiper 65 to remove any excess of a liquid adhesive 66 that may be taken up by the roll from the container in which a supply of adhesive is held, and a partial cover 67, on the container prevents entrance of dirt thereto. (See Fig. 11.)

Fixed on the spindle 62, adjacent the roll 63, is a spur pinion 68, these two elements filling the space between the brackets 61 and 65 meshing with the pinion is a gear 70 fixed

on the hub of a disc 71 frictionally tight on an eccentric spindle 72, having reduced ends passing through the brackets 61, one of the ends being secured by a nut 73 and the other carrying a knurled knob 74 by which the spindle may be manually adjusted.

Another disc 75 is mounted on the spindle 72, filling the space between the brackets and held by one or more screws 76 to the adjacent disc 71.

The disk 71 (see Fig. 12) has an undercut groove in its periphery to receive a rubber ring 77 open at one point and clamped by a washer 78, held by screws 79 to the disc 71, and the gear 70 is held to the outer surface of the washer by screws 80.

Fixed frictionally tight on the hub of the disc 75 is a spur gear 81 in mesh with the upper teeth on the rack 40 by which rotary motion is conveyed when the rack is actuated.

In the periphery of the disc 75 is a single notch 82, in which is engageable a pawl 83, pivoted on a pin 84 set in the outer adjacent side of the gear 81, the pawl being pressed into engaging position by a spring 85. (See Fig. 9.)

The disc 71 has in it a radial slot 86, in which is inserted a knife 87 having a sharply bevelled, serrated extending edge adapted to pass through a transverse opening in the rail 39 and sever the strip of banding material disposed between its upper flanges.

A dauber 88, of rubber or other soft substance adapted to periodically engage the adhesive supply roll 63, is set in a recess in the disc 71 to extend outwardly between the ends of the ring 77, closely adjacent the front edge of the knife 87, the dauber being supported by a stem 89 slidably contained within the disc and pressed outwardly by a spring 90 to the limit of a slot 91 and controlled by a pin 92, passing through the disc.

It is to be noted that the dauber stem is disposed at an angle tangentially of the spindle 72, the arrangement being such that the heel of the dauber, which is of lesser width than the banding strip, makes yielding contact with the strip just prior to its being severed by the knife.

Below the cutting blade, at the instant of its operation, the beam is supported on a roll 93 having reduced ends 94 to clear the gears and racks, and extending pintles 95 journalled in the plates 37 and 41.

On the outer sides of the plates 37 and 41 are the spacers 56, beyond which are plates 97 bent laterally outward at right angles as at 98, and then extended in parallel towards the front, as at 99, these extensions being rolled outwardly and extended downwardly, as at 99', to reach slightly beyond the elements 59.

The disc 29 is provided with a sinuous cam groove 101 in which operates a roller 102, carried on the end of an arm 103 forming part of a bell-crank lever pivoted at 104 on the upright of the machine.

The other, angularly disposed arm 106 of the lever is connected by a link 107 to a clevis block 108 having in its forked lower portion a pin 109 on which a spur pinion 110 is rotatably mounted.

Fixed on supports reaching from the column 22 is a vertical rack 111 engaging the teeth of the pinion on one side, and similarly engaging the pinion on the opposite side is another rack 112 secured to a vertical plunger or elevator 113 guided by a slot 114 in the column, central with relation to the shafts 24 and 25.

Due to the interposition of the pinion 110 between the fixed rack 111 and slidable rack 112, it will be seen that the latter rack and plunger will be moved twice the distance and at double the speed of the clevis block 108.

Mounted on top of the plunger 113 is a table 115 having attached at its front edge an angle bracket 116, carrying pivots 117 by which is connected a pair of opposed gripping fingers 118 pressed normally inward towards each other by springs 119, these fingers engaging the end of the banding strip when the plunger is in a raised position.

A pair of rails 120, are floatingly supported to extend longitudinally at the front of the machine, and the front rail has a downwardly offset arm 121, bent towards the column 22, as at 122, and then towards the forward end, as at 123, terminating in a hook 124 to receive a tension spring 125 attached at its upper end to a pin set in the column.

A guide bracket 126, attached to the column, has in its upper portion an adjusting screw 127 to limit the rise of the rail 120 as drawn up by the spring.

Fixed in the arm 121 is an adjustable stud 128, against which the table 115 contacts when in its lowermost position, causing depression of the bar 120, and secured on the arm 122 is an upright post 129 in which is fixed a sharp pointed pin 130, adapted to pierce the banding strip.

The post 129 has on its inner side, at the top, a pair of guide fingers 131 to turn the paper band upwardly when released from the finger 118, such release occurring by contact of the inner, cam-like portions of the fingers with the sides of the post, as will be later described.

The rails 120 are connected by a thin plate 132 forming a guide way and are further connected on their outer sides by looped clips 133 and 134, the latter, rear clip, having upwardly extending ends in

which is set a pivot pin 135 resting freely in plate brackets 136 fixed to the frame of the machine.

Secured to the inner sides of the clips 133, and 134, are guide strips 137, and there- 70 above is another plate 138 fixed between a second pair of rails 139, also attached to the clips, these rails and plate being curved upwardly at their front ends.

The plate 138 is narrowed and extended 75 beyond the upper rail ends at the front, as at 140, and attached to the forward inner side, at the end thereof is a block 141.

It is to be noted that the plate 138 is not parallel with the plate 132 but so arranged 80 as to present a wider space at the front than at the rear, the purpose being to slightly compress the packages of napkins as they are passed through the discharge chute composed of the elements 132, 137, and 138, 85 as will be more clearly apparent later on.

A pair of spaced bars 37 and 41 extend along the beam closely adjacent the racks and pivoted at 141 thereto are opposed grips 142 having inturned flanges 143 at 90 their lower ends and on their outer sides are raised cam-like projections 144, the grips being held normally extended by spring 145.

When the table 115 is moved downwardly 95 the lever arms 58 contact with the humps 144, closing the grips from the position shown in Fig. 3 to that of Fig. 4, the angled ends 59 extending over and past the edge of the bunched napkins.

The napkins are further guided by upright bars 146 extending down from the block 23 at a spaced distance from the face of the column 23.

In operation a roll of binding material, 105 as a tape-like banding strip of paper 53 coiled upon a core, is mounted on the shaft 52 disposed revolvably between the forks of the slotted supports 50 and held adjustably at a suitable height therein.

The strip extends from the roll towards the operative end of the structure, resting on the level upper surface of the rail 39, being guided by its flanges, below the adhesive applying device to make contact with the friction ring 77 and dauber 88 the friction ring impinging on the upper exposed surface of the strip 53, advancing it along the rail 39 a predetermined distance controlled by the circumference of the ring.

As has been seen, the dauber takes off a small quantity of adhesive from the disc 63, and deposits it on the strip immediately prior to the action of the knife 87, the severed portion of the strip advancing with the beam to extend past the table 115, at that time in a relatively downward position, and become impaled on the needle 130 at some distance from its outer end the strip 53 being held between the spring impelled fingers 130

118 on the bracket 116, as seen in Fig. 1, until the needle has entered the material.

Upon the recession of the rail 39 the strip and table rises to receive the folded napkins, a definite number being deposited, whereupon the cam actuated lever arms 58 pass over the bunch of napkins, the fingers 59 extending downward at the front of bunch, closing the strip at the rear and folding the outer end, at that time free from the needle 130, over the top the floating rail 120, carrying the needle, being depressed by contact of the plunger 113 with the adjustable stud 128, the arrangement being such as to release the needle prior to bending the banding strip about the bunched napkins.

Simultaneously the plate 138 is advanced, causing the block 141 to fold the rear portion of the strip upwardly and eventually 20 press it downwardly so that the adhesive carried by it is brought over the other end of the strip to be pressed by the curved portion of the plate 138, causing the ends of the strip to firmly adhere.

25 Thereafter the banded packages of napkins are progressively passed through the chute composed of the elements 132, 137 and 138, and ejected at the rear end, this movement being secured by the hook-like elements 30 59 carried by the beam and actuated by the cams 54.

The beam as a unit, is supported by the pivots or stems 30 and 31, and actuated by the latter to describe a gyratory path in a 35 horizontal position about the centers of the shafts 26 and 27.

The stem 30 moves within the slot 36 and carries the block 35 to which is secured the rack 42, thus rotating the pinion 49, and 40 translating a reverse motion to the rack 40.

The rack 40, being secured to the rail 39, transmits to it a reciprocating motion advancing and retracting the levers 56—59 in 45 timed relation to the action of the lever 106 which raises and lowers the table 115 by reason of the cam 101 in the shaft carried disc 29.

At the same time the upper teeth on the rack 40 engage the gear 70 to give it one 50 full turn, thus actuating the adhesive supplying devices, including the dauber 88 and knife 87 for severing a predetermined length of the banding strip, the dauber and knife however moving intermittently in one direction only, due to the pawl 83, while the gear is reversed and given a retrograde movement upon the rack being reversed, the pawl riding idly over the periphery of the disc 75.

Thus the banding strip is supplied with 60 adhesive, sheared from the roll, and advanced over the table 115, the table raised into receiving position, the band placed around the napkins as the table is lowered and eventually the packages ejected outwardly of the machine.

Obviously all of the several motions are accurately timed and as gears, racks, cams and levers are used throughout no slipping can occur or change, due to vibration of the parts, which are actuated at a high rate of 70 speed.

The foregoing disclosure is to be regarded as descriptive and illustrative only, and not as restrictive or limitative of the invention, of which obviously an embodiment may be 75 constructed including many modifications without departing from the general scope herein dictated and denoted in the appended claims.

Having thus described my invention, what 80 I claim as new and desire to secure by Letters Patent, is:—

1. In a banding machine, the combination with a frame having vertical guides, a work part delivering device above said guides, and a driven cam adjacent the guides, of a plunger movable in said guides, a table on said plunger to receive work parts, means actuated by said cam to raise and lower said plunger, means to project a strip of banding material over the face of the said table prior to delivery of work parts, and means operative during the descent of said plunger to wrap the banding strip around work parts deposited on the table. 90

2. In a banding machine, the combination with a frame having vertical guides, a work part delivering device above said guides, and a driven cam adjacent the guides, of a plunger movable in said guides, a table on said plunger to receive work parts, a rack 100 fixed on said frame, a second rack on said plunger, a pinion engaging between said racks, a block in which said pinion is mounted, a lever actuated by said cam operatively engaging said block, means to project a strip of banding material over said table when rising to work receiving position, means to fold the strip over the work parts when lowering, and means for expelling the banded 110 work parts outwardly from the machine.

3. In a banding machine, a beam moving in a gyratory path in horizontal planes, a table movable reciprocatively in a vertical plane in timed relation to said beam, means 11 for feeding a strip of banding material from said beam to said table, means for supplying an adhesive to said strip, means for severing the strip, and means for folding the strip around articles delivered on said table. 12

4. In a banding machine, a beam moving in a gyratory path in horizontal planes, a table movable reciprocatively in a vertical plane in timed relation to said beam, at an accelerated speed, means for applying an adhesive, cutting and advancing a strip of banding material from said beam to the top of said table to receive goods thereon, means for retaining the strip in adjusted position on the table, means for causing registration 13

of goods delivered on said table over the strip, means for folding the strip along the sides and over the goods, and timed means to remove the packaged goods from the table.

5. A banding machine comprising a horizontal beam moving in a gyratory path about fixed centers, a pair of opposed racks movable in opposite direction in said beam, a roll 10 of banding material carried on the beam, an adhesive supplying device actuated intermittently by one of said racks, means combined therewith to sever a predetermined length of banding material, a work receiving table, 15 means actuated by said beam for raising and lowering said table, means for advancing the severed strip of banding material over the table prior to raising the same, means for retaining the strip in position to receive 20 goods on the table, means for closing the strip around the goods, and means for removing the banded goods from the table and outwardly of the machine.
6. In a banding machine, the combination 25 of a frame, a beam movable therein and a roll of strip banding material carried on

said beam, of a channeled guide rail for the strip, a rack moved reciprocatively in said beam, a liquid adhesive container mounted on the beam, a gear actuated by said rack, 30 a pinion driven by said gear, a roll beside said pinion operative in said container, a frictional strip feed ring alongside said gear to engage the strip on said rail, means for driving said ring in one direction only by 35 said gear, said ring remaining quiescent upon reverse direction of the gear, a dauber set in said ring to impinge the periphery of said roll at each full turn of the gear, a knife in said ring adjacent said dauber to sever the 40 strip, and means to project the severed strip and adhesive thereon into position to become folded around a plurality of work parts.

7. In a banding machine, a delivery chute receptive of bound articles, said chute having 45 a level bottom and a top inclined downwardly towards the delivery end, and means for progressively passing the packages through the chute whereby they are subjected to compression.

JOHN O. HUNT.
